(57) **CLAIM**

The ornamental design for an air blower aerosol sprayer, as shown and described.

DESCRIPTION

FIG. 1 is a perspective view of an axial air blower aerosol sprayer;

FIG. 2 is a front elevation of an axial air blower aerosol sprayer;

FIG. 3 is a rear elevation of an axial air blower aerosol sprayer;

FIG. 4 is a left side elevation of an axial air blower aerosol sprayer;

FIG. 5 is right side elevation of an axial air blower aerosol sprayer;

FIG. 6 is a top elevation of an axial air blower aerosol sprayer; and,

FIG. 7 is a bottom elevation of an axial air blower aerosol sprayer.

The broken lines represent portions of the air blower aerosol sprayer and form no part of the claimed design.
